UNITED STATES PATENT OFFICE.

AURIN M. CHASE, OF SYRACUSE, NEW YORK, ASSIGNOR TO SYRACUSE CHILLED PLOW COMPANY, OF SYRACUSE, NEW YORK, A CORPORATION OF NEW YORK.

TEMPERING PROCESS.

1,091,120.

Specification of Letters Patent. Patented Mar. 24, 1914.

Original application filed March 7, 1899, Serial No. 708,071. Divided and this application filed August 24, 1903, Serial No. 170,575. Renewed July 28, 1911. Serial No. 641,173.

To all whom it may concern:

Be it known that I, AURIN M. CHASE, of Syracuse, in the county of Onondaga, in the State of New York, have invented a certain 5 new and useful Tempering Process, of which the following is a specification.

My invention relates to tempering processes, particularly suitable for carrying out by the apparatus set forth in U. S. Letters 10 Patent, No. 737079, dated Aug. 25, 1903, of the application for which patent this case is a divisional part, and has for its object a tempering process which enables the user to temper with great uniformity and in a 15 minimum space; and to this end, it consists in the manner of treatment hereinafter specifically pointed out and claimed.

In describing this invention, reference is had to the accompanying drawing, in which 20 like characters refer to corresponding parts in all the views.

Figure 1 is a plan view of the apparatus for carrying out my process forming the subject-matter of said Patent No. 737079. 25 Fig. 2 is a sectional view taken on line 2—2, Fig. 1.

It is well known to those skilled in the art, that it is exceedingly difficult, even for workmen of the greatest skill and expertness, to secure uniform results in successively tempering a number of articles for the reason that the fluid in which the articles are inserted when being tempered absorbs heat therefrom and is gradually 30 heated, thus effecting variation in the tempering of said articles. Indeed, the securing of uniform results in tempering is so difficult that in practice a considerable portion of a number of articles successively 35 tempered by even expert and skilled laborers must be retempered, thus necessitating reheating of the metal and additional labor and expense, and causing the metal to become less suitable for the desired purpose. 40 It is also well known that for the purpose of securing uniform results in tempering and requiring less heating of the articles to be tempered, it is customary to place ice within the tempering fluid and to also employ a number of tanks, or other receptacles, 45 for said fluid. When ice is used, the composition of the tempering fluid is continu-

ally varied as the ice melts, and ununiformity in tempering results. Moreover, if ice is used, even in large quantities, the temperature remains constant for a comparatively 55 short time only. The use of a plurality of tanks or receptacles containing tempering fluid also fails to add materially in effecting uniform tempering, since the temperature of the fluid in the respective tanks or receptacles is more or less variable and rises quickly as soon as tempering is commenced, especially when the size of the articles tempered is relatively large and the temperature 60 thereof high. Moreover, considerable space is occupied by the various tanks or receptacles, and the means for supporting the articles to be tempered must be capable of use at several points, or means must be 65 provided for conducting the tempering fluid from one tank or receptacle to another, which would not be necessary if a single tank or receptacle were sufficient. By my process, a minimum space is required for 70 tempering, and the tempering fluid is maintained substantially uniform in composition 75 and temperature.

The illustrated apparatus for carrying out my process consists of a receptacle for receiving the tempering fluid or liquid and the articles to be tempered, and an artificial refrigerating mechanism provided with a conduit arranged within the receptacle, and with means for passing an expandible refrigerating fluid through the conduit. Said receptacle is composed of chambers A B arranged side by side, the chamber A containing a tempering pool, being open at its top for admitting the articles to be tempered 80 and being provided with an inlet-opening a in the lower portion of its side a^2 adjacent to the chamber B, and with an outlet-opening a' in the upper portion of one of the sides a^3 arranged at an angle with the side a^2 . The chamber B cools the heated tempering fluid and is provided with an inlet B' for the fluid, a lateral branch b communicating with the outlet-opening a' of the chamber A, and a tortuous passage b' communicating at one end with the branch b and at its opposite end with the inlet-opening a of the chamber A. A revolute propeller-wheel C effects a positive circulation 85 90 95 100

of the tempering fluid from the outlet-opening *a'* through the branch *b* and the passage *b'* to the inlet-opening *a*.

The refrigerating mechanism consists of a compressor or pump *D*, a condenser *D'*, a receiver *D²*, expansion-refrigerating conduits *D³*, and connections between the compressor or pump, condenser, receiver and conduits for circulating an expansible-refrigerating fluid through said conduit. The construction of the compressor or pump *D*, condenser *D'*, receiver *D²*, and the connections between said parts, forms no feature of my present invention, and, consequently, it is unnecessary to describe the same. Said conduits *D³* are supported within the branches of the tortuous passages *b'* in the path of the tempering fluid passing therethrough.

In following out this process, the refrigerating mechanism constantly or intermittently maintains a lower temperature within the refrigerating conduits *D³* than that of the fluid or liquid circulating around said conduits. The temperature of said fluid is thus reduced, and if desired, ice is formed upon the exterior of the refrigerating conduits. The cooled tempering fluid is admitted to the lower portion of the tempering pool, the articles to be tempered are momentarily inserted into said pool through the opening in the top of the chamber *A*, and are then withdrawn and the upper surface of the tempering pool is removed and passes through the chamber containing the refrigerating conduits. Said tempering fluid within the chamber *A* for receiving the article to be tempered may be maintained at any desired temperature, and, consequently, users of my apparatus may temper uniformly. Maintenance of the tempering fluid or liquid at a constant temperature is greatly facilitated by first forming ice upon the refrigerating conduits within said liquid and then causing the refrigerating mechanism to abstract sufficient heat from the liquid to prevent melting of the ice irrespective of the masses and temperatures of the articles being tempered. It will be apparent to those skilled in the art, that as the tempering pool should ordinarily be maintained at a temperature considerably lower than that of the atmosphere and preferably a few degrees above or below freezing point, it is necessary to abstract from the tempering liquid more heat than imparted thereto by the article momentarily immersed therein, since more or less heat is imparted to the tempering fluid by the atmosphere. Therefore, ordinarily, my process includes abstracting from the tempering fluid a greater amount of heat than imparted thereto by the articles to be tempered.

Having thus fully described my invention, what I claim as new and desire to secure by Letters Patent, is:—

1. The herein described process for maintaining a fluid tempering bath substantially uniform in composition and temperature, and such temperature at approximately the freezing point of water, consisting in confining the bath in a container, disposing a minor portion of the bath in the form of an unobstructed pool for the reception of the articles to be tempered, and constantly circulating through a major portion of the bath, located outside of said pool, an expansible refrigerating medium, substantially as and for the purpose described.

2. The herein described process for maintaining a fluid tempering bath substantially uniform in composition and temperature, and such temperature at approximately the freezing point of water, consisting in confining the bath in a container, disposing a minor portion of the bath in the form of an unobstructed pool for the reception of the articles to be tempered, constantly circulating through a major portion of the bath located outside of said pool an expansible refrigerating medium and positively circulating the fluid of the entire bath, substantially as and for the purpose specified.

3. The herein-described process of tempering metallic articles, which consists in providing a bath of liquid, circulating an expansible refrigerating medium therethrough to form ice within the bath, immersing in said bath the first of a series of articles to be treated, maintaining a sufficient circulation of refrigerating medium to counteract the heat given off by the article under treatment and the heat taken from the surrounding atmosphere, removing the first article immersed from the bath, and then immersing in the bath another article of the series to be treated.

4. The herein-described process of tempering, which consists in providing a bath of liquid; immersing therein, in succession, a number of articles to be treated; and circulating therethrough a refrigerating medium so proportioned thereto and to the heat given off by said articles that a portion of the liquid of the bath, less than the whole, will be congealed and maintained in substantially a congealed condition.

In testimony whereof, I have hereunto signed my name in the presence of two attesting witnesses, at Syracuse, in the county of Onondaga, in the State of New York, this 22nd day of August, 1903.

AURIN M. CHASE.
